Jeffrey D. Moy(57) **CLAIM**

I claim the ornamental design for a water jet propulsion pool cleaner, as shown and described.

DESCRIPTION

FIG. 1 is a perspective view of a water jet propulsion pool cleaner;

FIG. 2 is a front view of the water jet propulsion pool cleaner;

FIG. 3 is a rear view of the water jet propulsion pool cleaner; FIG. 4 is a left-side view of the water jet propulsion pool cleaner;

FIG. 5 is a right-side view of the water jet propulsion pool cleaner;

FIG. 6 is a top view of the water jet propulsion pool cleaner; and,

FIG. 7 is a bottom view of the water jet propulsion pool cleaner.

The broken lines in the drawings depict portions of the water jet propulsion pool cleaner that form no part of the claimed design.
